UNITED STATES PATENT OFFICE.

BERNARD F. WRIGHT, OF DETROIT, MICHIGAN, ASSIGNOR TO FEDERAL MOTOR TRUCK COMPANY, OF DETROIT, MICHIGAN, A CORPORATION OF MICHIGAN.

DESIGN FOR A VEHICLE RADIATOR ORNAMENT.

54,622.

Specification for Design.

Patented Mar. 9, 1920.

Application filed June 16, 1919. Serial No. 304,712. Term of patent 14 years.

To all whom it may concern:

Be it known that I, BERNARD F. WRIGHT, a subject of the King of Great Britain, residing at Detroit, in the county of Wayne and State of Michigan, have invented a new, original, and ornamental Design for a Vehicle Radiator Ornament, of which the following is a specification, reference being had to the accompanying drawing, forming part thereof.

In the drawing, which shows in elevation, the ornament applied to the front of a radi-

ator, 1 indicates the radiator, and 2 a structure located in advance of the radiator and providing the ornamentation thereof, 3 indicating arms projecting rearward at the sides of the radiator.

I claim:

The design for a vehicle radiator ornament, as shown and described.
